UNITED STATES PATENT OFFICE.

OSCAR H. HICKS, OF CHICAGO, ILLINOIS, ASSIGNOR TO WHITE PRODUCTS COMPANY, OF CHICAGO, ILLINOIS, A CORPORATION OF ILLINOIS.

DESIGN FOR A RADIATOR-CAP.

• 56,699.

Specification for Design.

Patented Nov. 30, 1920.

Application filed July 29, 1920. Serial No. 399,905. Term of patent 14 years.

To all whom it may concern:

Be it known that I, OSCAR H. HICKS, a citizen of the United States, residing at Chicago, in the county of Cook and State of Illinois, have invented a new, original, and ornamental Design for Radiator-Caps, of which the following is a specification, reference being had to the accompanying drawing, forming a part thereof.

In the drawing Figures 1 and 2 illustrate

in side elevation and top plan view respectively a radiator cap embodying the present design.

I claim:

The ornamental design for a radiator cap, as shown.

OSCAR H. HICKS.
